UNITED STATES PATENT OFFICE.

EVERETT WORTHINGTON, OF CHICAGO, ILLINOIS, ASSIGNOR TO BRANDES LABORATORIES, INC., OF NEWARK, NEW JERSEY, A CORPORATION OF NEW JERSEY.

DESIGN FOR A RADIOCABINET.

Application filed June 2, 1928. Serial No. 26,973. Term of patent 14 years.

To all whom it may concern:

Be it known that I, EVERETT WORTHINGTON, a citizen of the United States of America, residing at Chicago, in the county of Cook and State of Illinois, have invented a new, original, and ornamental Design for Radiocabinet, of which the following is a specification, reference being had to the

accompanying drawing, forming part thereof.

The figure is a perspective view showing my design of radiocabinet.

I claim:

The ornamental design for a radiocabinet as shown.

EVERETT WORTHINGTON.
